UNITED STATES PATENT OFFICE.

FREDERICK G. BENSKIN, OF CANTON, OHIO.

DESIGN FOR A MOLDER'S FILLET.

SPECIFICATION forming part of Design No. 23,626, dated September 4, 1894.

Application filed July 25, 1894. Serial No. 518,588. Term of patent 3½ years.

To all whom it may concern:

Be it known that I, FREDERICK G. BENSKIN, a citizen of the United States, and a resident of Canton, county of Stark, State of Ohio, 5 have invented and produced a new Design for Molders' Fillets, of which the following is a full, clear, and exact description, reference being had to the accompanying drawings, making part of this specification.

- 10 My new design relates to molders' fillets. In the accompanying drawings,—Figure 1, is an enlarged perspective view of my design, and Fig. 2, is a cross sectional view of the same.
- 15 My design comprises a molder's fillet as shown in the accompanying drawings, and

the leading feature is a strip A, having a flat horizontal base *a*, converging inclined flat sides *b* at an acute angle to the base and terminating in a rib *c*, the sides of which are at 20 an obtuse angle to the portions B and meet at a point *d*.

What I claim is—

The design for a molder's fillet as herein shown and described.

In testimony whereof I have hereunto set my hand this 24th day of July, A. D. 1894.

FREDERICK G. BENSKIN.
